UNITED STATES PATENT OFFICE.

HENRY SIEBEN, OF KANSAS CITY, MISSOURI, ASSIGNOR OF ONE-FIFTH TO L. E. WYNE,
OF KANSAS CITY, MISSOURI.

SEWER-CLEANER.

1,132,690.

Specification of Letters Patent. Patented Mar. 23, 1915.

Application filed October 17, 1913, Serial No. 795,809. Renewed January 14, 1915. Serial No. 2,278.

To all whom it may concern:

Be it known that I, HENRY SIEBEN, a citizen of the United States, residing at Kansas City, in the county of Jackson and State 5 of Missouri, have invented certain new and useful Improvements in Sewer-Cleaners, of which the following is a specification.

My invention relates to improvements in sewer cleaners, and my object is to provide a 10 simple and efficient device of this character whereby sewers clogged with foreign matter can be readily cleansed thereof.

The cleaner is self-adjustable, so that it 15 may readily accommodate itself to any inequalities existing in the interior of a sewer in which it is operated. The device is also manually adjustable, so that it may accommodate sewers of different diameters.

In order that the invention may be fully 20 understood, reference will now be made to the accompanying drawings, in which:

Figure 1 is a broken vertical section of a sewer, the cleaner therein, a hose connection to said cleaner, and means for drawing the 25 cleaner through the sewer in two directions. Fig. 2 is a broken section of a shaft and a draft rod connected to said shaft for the purpose of drawing the cleaner through a sewer. Fig. 3 is a broken vertical section 30 on line III—III of Fig. 1. Fig. 4 is a broken longitudinal section of the cleaner in position in a section of sewer. Fig. 5 is a cross section on line V—V of Fig. 4. Fig. 6 is a cross section on line VI—VI of Fig. 4. 35 A designates a sewer, and B designates two manholes leading into said sewer.

In carrying out the invention, I employ a tubular body 1, provided at its rear end 40 with a nipple 2, having a hose coupling 3 to which one end of a hose 4 is coupled. The forward portion of body 1 is provided with a nozzle member 5, having a plurality of forwardly tapering discharge holes 6 and rigidly-secured to the tubular body 1 by pins 45 7, or other suitable means.

8 designates a plurality of horizontal bars provided near their ends with rollers 9 to traverse the interior of the sewer A.

The horizontal bars 8 are pivotally-mounted upon a plurality of links 10, 11 and 12, which in turn are pivotally-secured to rings 13, 14 and 15, respectively, embracing the tubular body 1. Links 13 and 15 are rigidly secured to the tubular body 1 55 and ring 14 is slidable upon said tubular

body 1 to allow movement of the links, so that rollers 9 may accommodate themselves to any inequalities existing within the interior of the sewer. Rollers 9 are yieldingly held in contact with the interior of the 60 sewer through the intermediary of an expansion spring 16, embracing the tubular body 1 and bearing at its ends against the ring 14 and a collar 17, which latter is adjustably-secured upon the tubular body 1 by 65 a set-screw 18, so that said collar may be adjusted to regulate the pressure of the spring 16 upon the ring 14.

19 designates a shaft journaled in the nozzle member 5 and a spider 20, which latter 70 like said nozzle member 5 is rigidly fixed within the tubular body 1. Shaft 19 is provided at its rear end with a thrust bearing 21 to prevent it from moving forwardly in its bearings 5 and 20. 75

22 designates a turbine rigidly mounted upon shaft 19 immediately in advance of the nozzle member 5, so that the water discharged therefrom will impinge against the blades of the turbine with considerable force 80 and rotate the same at suitable speed.

23 designates a plurality of toggles, each pair of which carries a blade 24 and is pivoted at its ends to members 25 and 26 mounted upon shaft 19 in advance of the turbine 85 22.

The toggles 23 are automatically expanded by an expansion spring 27, embracing shaft 19 and interposed between the turbine 22 and member 26, which latter is slidable on shaft 19 to permit the blades 24 to yield when contacting obstructions, such for instance as cement, too firmly secured to the inner surface of the sewer for dislodgment by said blades. The toggles 23 are manually 95 expanded or contracted to fit sewers of different diameters by sliding the member 25 forward or backward on the shaft 19 and then securing said member at any point of its adjustment by means of a set-screw 28 100 adapted to enter any of the threaded holes 29 in the forward portion of the shaft 19. The pressure of spring 27 upon member 26 is regulated by a split collar 30, adjustably secured to shaft 19 and provided with a rearwardly extending driving arm 31 engaging the member 26 to cause it to rotate with the shaft 19.

32 designates a flexible draft-rod for drawing the cleaner through a sewer. Said 110

draft-rod 32 is provided at its forward end with a ball 34, which latter is swiveled in a socket formed in the forward end of shaft 19 and the rear end of a cap 35 screwed into a fitting 36, fixed to the forward end of the shaft 19 by a pin 37, or other suitable means. Cap 35 is provided at its front side with a bushing 38, having a forwardly-flaring opening 39 to allow movement of the draft-rod 32, which extends through said opening and an opening in the cap 35.

Dirt and other foreign matter is prevented from getting between the ball 34 and its socket by a washer 40 snugly embracing the draft-rod 32 and loosely interposed between the cap 35 and the rear end of the bushing 38, so that said washer may move with the draft-rod.

Any suitable means may be employed for forcing or drawing the cleaner through a sewer. In the drawings, I have shown means for pulling the cleaner through the sewer in two directions, consisting of windlasses 41 and 42 and cables 43 and 44, cable 43 being attached at its ends to windlass 41 and loop 33, and cable 44 being attached at its ends to windlass 42 and a coupling 45 on hose 4. The windlasses 41 and 42 are mounted over the manholes B upon frames 46 and 47, respectively. Cable 43 runs around guide sheaves 47 and 48, the former being mounted upon an adjustable jack 49 engaging the interior of the sewer, and the latter being mounted upon a standard 50 secured at its upper end to the frame 46 and provided near its lower end with legs 51 which bear against the interior of the manhole B. Cable 44 runs around a guide sheave 52 mounted upon an adjustable jack 53, engaging the inner side of the sewer and braced by a standard 54. The upper end of the hose 4 is connected to a hydrant not shown.

The operation of the cleaner briefly is as follows: After the cleaner has been placed in position in the sewer, water is admitted to the hose 4 and one of the windlasses 41 is operated to draw the cleaner from one manhole to the other. The water from the hose 50 passes into the tubular body 1, and in passing through the nozzle member 6 is discharged with considerable force against the turbine 22 which is thus rotated and in turn rotates the shaft 19, the toggles 23, and the blades 24. The revolving blades 24 loosen and dislodge refuse and tear away any vegetation that may be rooted in the sewer, the water discharged from the turbine contributing to the effectiveness of the operation. After the cleaner has been drawn to one manhole, the windlass at the opposite manhole is operated to return the cleaner to the starting point. The hose and the ropes may then be disconnected from the apparatus and moved to an adjacent portion of the sewer.

While the device is primarily designed for cleaning sewers, it may be used to advantage for cleaning the interior of water mains and other conduits, and for this purpose I provide the toggles 23 with chains or cables 70 55, armed with serrated balls or disks 56 to coact with said toggles and the blades 24 in removing deposits of foreign matter.

While I have shown and described the preferred form of my cleaner, it is obvious that changes may be made in the combination, arrangement and construction of parts as properly fall within the spirit and scope of the appended claims.

Having thus described my invention, what I claim and desire to secure by Letters Patent is:

1. In a sewer cleaner, a driven shaft, and a toggle driven by said shaft and having forwardly converging cutting edges. 85

2. In a sewer cleaner, a driven shaft, a member manually adjustable upon said shaft, means for securing said member at any point of its adjustment, a companion member slidable upon the shaft, a collar fixed to the shaft to limit the sliding movement of said companion member and to drive the same, yielding means to normally press the slidable member toward said collar, and sewer cleaning elements operably-secured to the adjustable member and the companion member. 90 95

3. In a sewer cleaner, a driven shaft, a member manually adjustable upon said shaft, means for securing said member at any point of its adjustment, a companion member slidable upon the shaft, means fixed to said shaft to limit the sliding movement of said companion member and to drive the same, resilient means to normally hold the companion member in contact with said means, toggles operably-secured to the adjustable member and the companion member, and cutting elements on said toggles. 100 105

4. A sewer cleaner, consisting of a tubular body, means for guiding said body through a sewer, arms pivotally-connecting said guiding means to the tubular body, a ring slidably on the tubular body, arms pivotally-connected to said ring and the guiding means, resilient means to force said ring toward the arms pivoted thereto, and sewer cleaning elements operably-connected to the tubular body. 110 115

5. A sewer cleaner, consisting of a tubular body, a driven shaft journaled therein, sewer cleaning elements driven by said shaft, longitudinal bars adjacent the tubular body, arms pivotally-connected to said longitudinal bars and the tubular body, a ring slideable on the tubular body, arms pivotally-connected to said ring and the guiding means, and resilient means to force said ring longitudinally upon the tubular body. 120 125

6. In a sewer cleaner, a driven shaft, ob- 130

struction removing means mounted upon said shaft, and cables attached to said obstruction removing means and adapted to be thrown by centrifugal force against the 5 interior of a sewer.

7. In a sewer cleaner, a driven shaft, obstruction removing means mounted upon said shaft, cables attached to said obstruction removing means, and weights at the 10 free ends of said cables adapted to be thrown by centrifugal force against the interior of a sewer.

8. In a sewer cleaner, a driven shaft, a toggle driven by said shaft and having forwardly-converging cutting edges, and manual means for expanding or contracting said toggle. 15

In testimony whereof I affix my signature, in the presence of two witnesses.

HENRY SIEBEN.
